UNITED STATES PATENT OFFICE.

WALTER MILFORD, OF SYRACUSE, NEW YORK, ASSIGNOR, BY MESNE ASSIGNMENTS,
TO GEORGE C. YOCUM, OF SCRANTON, PENNSYLVANIA.

AUTOMATIC TELEPHONE PAY-STATION.

1,053,849.

Specification of Letters Patent. Patented Feb. 18, 1913.

Application filed November 29, 1910, Serial No. 594,754. Renewed July 17, 1912. Serial No. 710,055.

To all whom it may concern:

Be it known that I, WALTER MILFORD, of Syracuse, in the county of Onondaga, in the State of New York, have invented new and useful Improvements in Automatic Telephone Pay-Stations, of which the following, taken in connection with the accompanying drawings, is a full, clear, and exact description.

10 This invention relates to certain improvements in automatic pay stations for telephone toll service, "pay-as-you-enter" street cars, coin controlled vending machines and other uses to which such a device might be applied for automatically rendering some service upon the prepayment of a coin or coins of the same or different denominations. In the use of this class of instruments it is well known that a considerable percentage of spurious coins or disks commonly known as "slugs" are substituted for the genuine coins and this is particularly true of telephone toll stations which are usually located in booths and other isolated places where they afford ample opportunity for the use of spurious coins or slugs without liability of detection and results in a considerable loss to the owners or operators of the system.

15 The main object of my present invention is to produce a simple, compact and efficient coin receiving device by which the slugs or counterfeits will be separated from the genuine coins and returned to the depositor without rendering any service and at the same time to enable the good coins to perform the service or functions for which they were intended and to be finally deposited in a concealed receptacle out of reach of the operator and separate from the spurious coins or slugs.

The details of the invention will be made clear from the following description, taken in connection with the accompanying drawings.

20 In the drawings Figure 1 is a perspective view of a pay station embodying the various features of my invention as used for telephone service. Fig. 2 is a top plan of the same instrument omitting the telephone and showing the top wall of the case removed

to disclose the interior mechanism. Fig. 3 is a top plan similar to Fig. 2 omitting the guide ring for the coins and showing particularly the coin chutes, and signals associated therewith and also the slug receptacle and guide leading therefrom to the exterior of the case. Fig. 4 is an enlarged side elevation of the device shown in Fig. 1 except that the telephone is omitted and the adjacent side of the case is removed to disclose the interior mechanism, one of the coin chutes and portion of the signal and also a portion of the return chute and receptacle for the slugs being shown partly in section. Fig. 5 is an enlarged sectional view taken on line 5—5, Fig. 1. Fig. 6 is a side elevation of the developed guide ring showing several coin guides, the inlets and portions of the coin chutes being shown in section. Fig. 7 is an enlarged horizontal sectional view of the guide ring through portions of the several coin guides. Figs. 8 and 9 are sectional views of two of the coin chutes and adjacent portions of the guide ring and coin receptacle, one of the signals being shown in section in Fig. 8 and the other signal in elevation in Fig. 9. Fig. 10 is a sectional view of the upper portion of one of the coin chutes and adjacent portion of the guide ring with which it is connected. Fig. 11 is an elevation of a portion of the guide ring showing particularly one of the discharge openings for the slugs and the floating guide rail associated therewith. Fig. 12 is a horizontal sectional view of a portion of the same guide ring taken on line 12—12 Fig. 11. Figs. 13 and 14 are vertical sectional views of one side of the guide ring taken on line 13—14 Fig. 11, the floating rail being shown in normal position in Fig. 13 for guiding the coin past the slug opening while Fig. 14 shows the rail as slightly raised by the passage of the slug through the opening. Figs. 15 and 16 are respectively a top plan and transverse sectional view of a modified form of guide ring having slug openings on the inside of the coin guides.

This apparatus comprises an inclosing case —1— having a plurality of, in this instance three, separate inlet guides or gages

—2, —3— and —4— preferably located in or upon the top of the case and gaged to the maximum sizes of coins of different denominations such as nickels, dimes and 5 quarter-dollars and thereby preventing the insertion of any coins or disks which may be of greater diameter or size than the genuine coins. These inlets are further distinguished one from the other by suitable characters 10 as numerals 5, 10 and 25 printed or otherwise impressed upon the guides or adjacent portions of the case to indicate the point of entrance of the required coin. Within the casing, and preferably secured 15 to the under side of the top thereof, is arranged a member B, preferably in the form of a cylinder, and comprising an inner ring 5, having coin guideways in its periphery, and an outer ring 5^a forming the outer walls 20 of said guideways. In the device illustrated in the drawing the member B is provided with three guideways 6, 7 and 8, which are spirally arranged, inclining downward in the same general direction from their respective inlets 2, 3 and 4, at the top of the casing, to suitable coin chutes 9, 10 and 11 at the lower side of said member, the outlet end 25 of each guideway extending some distance beyond the vertical plane of the inlet of the next adjacent guideway, thereby permitting the guides to be made of considerable length within a comparatively small and compact space. It will be evident that coins moving by gravity through the guideways will be 30 thrown by centrifugal force against the outer walls of the guideways. The transverse dimensions of each coin race or guide are somewhat larger than the coin which it is adapted to receive and therefore larger 35 than the mouth of the inlet through which the coin is first inserted so as to permit such coin to roll or gravitate freely from the inlet to the outlet without liability of retardation by excessive friction.

40 45 The intermediate portions of the outer walls of the coin guides 6, 7 and 8 are provided with circumferentially elongated slots or openings 12, 13 and 14 of slightly less vertical width than the diameter of the 50 coins which are adapted to pass through said guides and therefore of slightly less width than that of their respective inlets 2, 3 and 4 so that any slugs or disks of even 55 slightly less diameter or size than that of the designated coins will be thrown outwardly or laterally through said slots or openings and away from the coin guides while the perfect coins will pass entirely 60 through the guides and into their respective chutes thereby automatically separating the undersized disks or slugs from the coins. In some instances these disks or slugs may 65 be of exactly the same diameter as the vertical width of the slot or opening or may be slightly eccentric under which conditions

they are more or less liable to become wedged or frictionally caught between the lower and upper walls and thereby fail to pass through such opening. In order to obviate this liability the outer walls of the 70 coin guides are provided with vertically movable guide rails or floating sections 75 —15— constituting the top walls of their respective openings —12, —13— and —14— and preferably formed of light or thin sheet metal capable of being lifted by and under rolling momentum or centrifugal force of such slugs or disks sufficiently to allow the latter to pass out through their respective openings. Each floating section is normally 80 but loosely supported at its ends parallel with the bottom of its corresponding coin guides upon suitable shoulders —16— and is also loosely held against outward displacement by spring retaining fingers —17— 85 which are secured to the main supporting ring at opposite ends of the adjacent slug-opening and provided with narrow bearings in contact with the outer faces of the ends of said floating section so that the latter may 90 be lifted by the slightest upward pressure against its lower edge.

The coin chutes —9—, —10 and —11— are secured in a more or less upright and inclined position within the case —1— and upon a suitable supporting plate or horizontal partition —18— with their upper ends in registration with the outlet ends of their respective coin guides —6—, —7— and —8— and their lower ends discharging 100 through openings in the plate —18— into an underlying receptacle or money drawer —19— which, in this instance, is common to all of the chutes and is normally locked within the base of the case to properly conceal and protect the money against malicious removal.

One of the important features of this invention is that the spurious coins or slugs are not only automatically separated from the monetary coins in transit through their respective coin guides but are also automatically returned to the exterior of the case in full view of the operator without performing the function for which they 110 were intended and for this purpose the slugs discharged from the openings 12, 13 and 14 are caused to gravitate into underlying pockets —20— which converge downwardly and inwardly below and around the axis of 115 the ring —1— and discharge into an underlying hopper —21—. This hopper is preferably coaxial with and below the main guide-ring —5— and provided with downwardly and inwardly inclined or conical 120 sides terminating at the apex in a substantially flat slug-chute —22— which is arranged edgewise vertically and extends downwardly and laterally in an inclined 125 plane to a suitable outlet —23— in the ad- 130

jacent side of the case where the slugs are finally delivered into a receiving tray —24— on the exterior of said case.

In an apparatus of this character whether used in connection with telephone service, in coin controlled vending machine, pay-as-you-enter cars or in any other relation, it may be desirable to provide means such as signals operated by either the coins or slugs (or by both) to enable any one within hearing or seeing distance of the machine to detect any attempt to make improper use of the same by repeated use of slugs and for this purpose I have associated with the several coin chutes separate and audibly distinctive signals consisting, in this instance, of bells —25— and —26— and a gong —27— each having a portion thereof projecting a sufficient distance into its corresponding chute to be engaged by the coin in transit therethrough without liability of impeding the progress of such coin and it is clearly evident that a similar gong or bell may be similarly disposed in the path of movement of the slugs while in transit from the main guide ring to the receiving tray —24—. By this means any one stationed in or near the room in which the instrument is installed may readily detect any attempt to operate the instrument by the use of spurious coins or slugs and thereby prevent a repetition of such attempts.

In the particular instrument thus far described the slugs are discharged by gravity and centrifugal force through openings in the outer side of the main guide ring but it is clearly evident that the objects of this invention may be carried out by various modifications such for example as that shown in Figs. 15 and 16, in which is illustrated a frusto-conical member B', having its apex at the top, said member comprising an outer ring 30, having the spirally arranged guideways 6, 7 and 8 on its inner face, and a ring 30^a forming the inner walls of the guideways, said latter ring being provided with elongated openings —9—, —10— and —11— through which the slugs may readily gravitate into the underlying hopper —21— and thence through the slug chute —22— and outlet —23— to the external receiving tray —24— while the monetary coins will be delivered into their respective chutes —12—, —13 and —14— and thence into the concealed receptacle —15— in substantially the same manner as previously described.

The operation of my invention will now be readily understood with reference to the foregoing description and accompanying drawings and it is evident that the detail construction shown and described may be materially modified without departing from the spirit of my invention and therefore I do not limit myself to the exact construction

and arrangement of the various parts of the device herein specifically set forth.

What I claim is:

1. A member having a circular wall with a plurality of spirally arranged coin guideways therein, each guideway having a lateral opening for the escape of coins or slugs under a given size. 70

2. A member having a circular wall with a plurality of spirally arranged coin guideways therein, each guideway extending only part way around said member and each guideway having a lateral opening for the escape of coins or slugs under a given size. 75

3. A member having a circular wall with a plurality of spirally arranged coin guideways therein, each guideway extending from end to end of and only part way around said member, and each guideway having a lateral opening for the escape of coins or slugs 80 under a given size. 85

4. A casing having a top provided with a plurality of coin slots, and an annular member supported beneath said top and having a plurality of spirally arranged coin 90 guideways meeting said slots, each guideway having a lateral opening for the escape of coins or slugs under a given size.

5. A member having a circular wall with a plurality of spirally arranged coin guideways, each guideway having a lateral opening in one side, the upper wall of each opening comprising a guide rail adapted to yield to upward pressure. 95

6. A member having a plurality of coin 100 guideways therein, said member comprising two rings arranged one within the other, one of said rings having spiral grooves formed therein, and the other ring extending over said grooves and having lateral 105 openings opposite the grooves for the escape of coins under a given size.

7. A member having a plurality of coin guideways therein, said member comprising two rings arranged one within the other, 110 one of said rings having spiral grooves formed therein, the other ring extending over said grooves and having lateral openings opposite the grooves for the escape of coins under a given size, and guide-rails, 115 adapted to yield to upward pressure, forming the upper walls of said openings.

8. An inclined coin guide having an opening in one side and a loosely supported guide-rail forming the upper wall of the 120 opening, said guide rail being adapted to move so as to enlarge the opening in response to the pressure of a slug or coin passing through the guide and bearing against the under side of said rail. 125

9. A spirally arranged coin guide having an opening in one side and a loosely supported guide-rail forming the upper wall of the opening, said guide rail being adapted to move so as to enlarge the opening in re- 130

sponse to the pressure of a slug or coin passing through the guide and bearing against the under side of said rail.

10. An inclined coin guide disposed edge-wise vertically and having an opening in one side, and a loosely supported guide rail forming the upper wall of the opening, said guide rail being adapted to move vertically, to enlarge the opening, in response to the

pressure of a slug or coin passing through 10 the guide and bearing against the under side of said rail.

In witness whereof I have hereunto set my hand on this 27th day of October 1910.

WALTER MILFORD.
